CARBON HOLDER

Robert L. Tanson, Oakland, Calif., assignor of
one-half to Elmer C. Hanks

Application March 13, 1945, Serial No. 582,519

2 Claims. (Cl. 176—119)

1

This invention relates to devices for holding the carbon electrodes employed in arc light mechanisms, and more particularly to carbon holders for use with the arc light mechanisms of motion picture machines.

Considerable effort has been exerted in the past to developing carbon holders capable of firmly gripping one end of a carbon electrode without danger of breaking it, and in such a manner that it can be easily and quickly removed for replacement. Another objective has been to develop carbon holders having the above characteristics and the additional advantage that as much usable length of the electrode as possible is left projecting beyond the tip of the holder so as to permit use of the carbon for a maximum of its length. Because carbon holders must hold an electrode securely and maintain it in proper alignment, the prior art devices have been constructed with the carbon engaging or receiving portion as an integral part of the main holder unit. Frequently carbon receiving portions are inadvertently burned and spoiled through carelessness or in attempts to consume as much of the length of the electrodes as possible before discarding the stubs, and since this injury will thereafter prevent the proper gripping and positioning of an electrode, the entire unit must be discarded and replaced.

An object of the invention is to provide a carbon holder of such a design that the end portion of the holder subject to burning may be easily and quickly removed and replaced.

Another object of the invention is to provide a carbon holder having an easily and quickly removable end portion of simple and inexpensive construction, whereby accidental burning thereof will occasion the smallest possible replacement cost and delay.

A further object of this invention is to provide an inexpensive carbon holder that will firmly hold a carbon electrode in alignment without danger of breaking it, while leaving the greatest possible length thereof exposed for use.

Still a further object of the invention is to provide a carbon holder with the above mentioned features that is compact, convenient to use, and durable, and that may be readily associated with standard arc light mechanisms.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings:

2

Figure 1 is an elevation of a carbon holder embodying my invention and having a carbon electrode positioned therein.

Figure 2 is a view similar to Figure 1 but showing a portion of the device in section.

Figure 3 is a vertical section taken along the line 3—3 of Figure 1.

Figure 4 is an end elevation of the device as shown in Figure 1, taken looking at Figure 1 from the right.

Figure 5 is a fragmentary elevation, similar to a portion of Figure 1, but illustrating a modified form of control for an electrode clamping arm.

15 The holder of my invention in the preferred embodiment includes an elongated metallic body 6 having a bore 7 in which is fitted an electric conductor rod 8 by which the holder may be supported on the projection machine and connected to a suitable source of current. Rod 8 is preferably considerably longer than the body 6 and is positioned meditately therein so that portions 9 and 12 of the rod will project outwardly from what may be termed the rear and forward ends 13 and 14 respectively of the body. A setscrew 15 extending transversely through the body serves to retain the rod in desired position therein.

An electrode here shown in the form of a carbon 16 is arranged to be operatively positioned and held at the forward end of the body in end to end relation with rod 8, and means are provided for receiving and holding the carbon in such relationship substantially entirely independent and separate of the main body 6. Rod 8 and carbon 16 are preferably designed cylindrical and of the same diameter and in accordance with the present invention there is provided a sleeve 17 of electric conducting material designed to contain and receive within inside thereof the adjacent ends of the rod and carbon. Preferably the sleeve 17 is arranged for positioning completely exteriorly of the body, and as clearly shown in Figure 2, the sleeve is long enough to fully enclose the rod portion 12 and provide for receipt of a sufficient length of the carbon to insure its retention in the sleeve. Desirably the inside diameter of the sleeve is such as to provide for a snug fit of the carbon and rod in the sleeve and thus not only insure the firm positioning of the carbon in the sleeve but establish effective electrical connection between the rod and carbon.

55 Detachable fastening of the sleeve 17 to the rod may be effected in any suitable manner, and as here shown such fastening is provided for by means of a cotter pin 18 extending through openings 19 in the sleeve and a registering opening 21 in the rod. For clamping the carbon in the sleeve, a lever 22 is fulcrumed on the body and

formed with a bent end 23 having an arcuate surface 24 corresponding with and arranged to engage a side of the carbon and press the diametrically opposite side of the carbon against the adjacent surface of the sleeve. Desirably the end of the sleeve through which the carbon is received is formed with a slot 26 through which the end 23 of the lever may extend to operatively engage the carbon. Lever 22 is fulcrumed on the body by means of a pin 27 pivotally securing the lever intermediate its ends 23 and 28 in ears 29 formed on the body. Movement and positioning of the lever to place and hold the end 23 in engagement with the carbon in the sleeve may be effected by means of a nut 31 threaded on the screw 15 and positionable thereon to engage the end 28 of the lever as illustrated in Figure 2.

To insert an electrode in the holder described above, the nut 31 is screwed downwardly on the set screw 15 sufficiently to permit the bearing surface 24 of the bent end of the clamping lever to be retracted slightly from the position shown in the drawing. The electrode is then inserted in place and the nut 31 rotated on the set screw 15 until the bearing surface 24 of the lever is forced against the side of the electrode with the desired pressure for holding it against displacement or misalignment in use. To replace a consumed electrode, the nut 31 is merely rotated again to release the lever and permit removal of the stub to be discarded, and the new electrode is inserted in the manner described above.

It will now be clear that whenever the holder becomes damaged by reason of the electrodes being repeatedly allowed to burn close to the supported extremity, whether by inadvertence or for the purpose of securing economy in the consumption of the electrodes, simply replacing the sleeve will practically invariably render the holder as good as new. A damaged sleeve can be readily removed by merely withdrawing the cotter pin, substituting a new sleeve over the rod portion 12, and then replacing the pin. It will thus be evident, that a long life of the holder will be insured, and economy obtained in this regard as well as in the use of the electrodes. In this connection it should be noted that the sleeve is very simple in construction and can readily be formed from standard tubing stock. Furthermore, since the tube is separate of the main body, it can be made of material more conducive to cooperation with the electrode and not be restricted by the structural requirements that may be necessary for the parts of the main body.

A modified device for exerting the desired pressure of the lever against the electrode, is shown in Figure 5. In place of the nut 31, previously described, a helical spring 32 is positioned with one end around the set screw 15, and the spring is held under compression between the end 28 of the lever and the side of the body 6. A boss 33 is preferably formed on the lever in approximate alignment with the axis of the spring 32, and the other end 34 of the spring is fitted over the boss to hold the spring securely in position. With this arrangement, it is merely necessary to press the end 28 of the lever against the pressure of the spring to release an electrode for removal and to permit insertion of a new electrode.

I claim:

1. A holder for a rod-like electrode comprising an elongated metallic body having a bore extending entirely therethrough and being of a di-

ameter substantially corresponding to that of said electrode, a rod of substantially the same diameter of said electrode slidable longitudinally in said bore and having an end extending from said body, a sleeve arranged for positioning with an end against said body and having a bore of substantially the same diameter as the bore of said body and receiving said rod end in a portion thereof, means securing said rod and sleeve with the rod positioned in said sleeve as aforesaid, said sleeve receiving in another portion of its bore an end of said electrode and being provided with a slot in said portion exposing the electrode in the bore, a lever pivotally connected to said body having an arm with the free end thereof positioned to register with said slot when said sleeve is against said body as aforesaid and to engage the electrode when in the sleeve, means engaging said lever to releasably hold said arm in engagement with said electrode as aforesaid, and means for retaining said rod against longitudinal displacement in said body bore.

2. A holder for a rod-like electrode comprising an elongated metallic body having a bore extending entirely therethrough and being of a diameter substantially corresponding to that of said electrode, a rod of substantially the same diameter of said electrode slidable longitudinally in said bore and having an end extending from said body, a sleeve arranged for positioning with an end against said body and having a bore of substantially the same diameter as the bore of said body and receiving said rod end in a portion thereof, means securing said rod and sleeve with the rod positioned in said sleeve as aforesaid, said sleeve receiving in another portion of its bore an end of said electrode and being provided with a slot in said portion exposing the electrode in the bore, a lever pivotally connected to said body having two arms, one of said arms having a free end positioned to register with said slot when said sleeve is against said body as aforesaid and to engage the electrode when in the sleeve, means secured to said body and engageable with the other arm of said lever to releasably move said first mentioned arm and the end thereof into engagement with said electrode, said free end of the arm being formed to engage said sleeve to limit displacement of said sleeve relative to said body on longitudinal displacement of said rod relative to the body.
